UNITED STATES PATENT OFFICE.

DWIGHT G. McCARTY, OF EMMETSBURG, IOWA.

OFFICE APPLIANCE.

1,367,983.

Specification of Letters Patent.

Patented Feb. 8, 1921.

Application filed June 10, 1920. Serial No. 388,016.

To all whom it may concern:

Be it known that I, DWIGHT G. McCARTY, a citizen of the United States, and resident of Emmetsburg, in the county of Palo Alto 5 and State of Iowa, have invented a certain new and useful Office Appliance, of which the following is a specification.

The object of my invention is to provide an office appliance of simple and inexpensive 10 construction, particularly adapted for use as a "tickler" device.

More particularly it is my object to provide such an appliance including a base or support, an inclined supporting member 15 mounted thereon, a yielding fastening device mounted on said inclined member, a container, and means for holding a memorandum slip adjacent to the forward portion of said container.

20 With these and other objects in view, my invention consists in the construction, arrangement and combination of the various parts of the device, whereby the objects contemplated are attained, as hereinafter more 25 fully set forth, pointed out in my claims, and illustrated in the accompanying drawings, in which:

Figure 1 shows a side elevation of an office appliance embodying my invention.

30 Fig. 2 shows a front view of the same.

Fig. 3 shows a vertical, sectional view, partly broken away taken on the line 3-3 of Fig. 2.

Fig. 4 shows a detail sectional view, taken 35 on the line 4-4 of Fig. 1; and

Fig. 5 shows a plan view of the tickler slip used in connection with my office appliance.

In the form of my device disclosed in the 40 drawings, I have used the reference numeral 10 to indicate generally a flat base. Mounted thereon, near the rear portion thereof, is a rearwardly and upwardly extending supporting member 11, which may be mounted 45 between a block 12 behind the member 11, and a smaller member 13 in front of said member, for giving it rigidity.

Mounted on the base 10 and spaced forwardly from the support 11, is a receptacle 50 having a bottom 14, rearwardly inclined rear and front walls 15 and 16, end walls 17, and a vertical front wall 18 extending from the bottom 14 to the upper end of the front wall 16. Hinged to the receptacle, in the 55 manner which will be hereinafter described, is a cover member having the inclined front

and rear wall members 19 and 20, the side members 21, and the top member 22.

Fixed to the side walls 21 of the cover member, on the outside thereof, are downwardly extending arms 23. Secured to each side member 17 of the receptacle is a strip 24 arranged parallel with the wall 15, as shown, for instance, in Fig. 1. The strip 24 has a laterally and forwardly inclined 65 portion 25, having at its forward edge a forwardly inclined portion 26 parallel with the side wall.

In the portion 26 of each hinge element now under consideration, is an elongated 70 slot 27. Connected with each arm 23 is a double-headed pin or the like 28, extended through the slot 27 of the adjacent hinge element. By means of the construction just shown it will be noted that the cover member 75 may be swung upwardly and rearwardly and then slid downwardly behind the receptacle, where it will be out of the way while the device is in use.

Secured to the member 11, as at 29, are 80 spring clips 30 extending upwardly and having at their upper ends lateral extensions 31 projecting laterally beyond the member 11 to position where they may be conveniently grasped for pulling the spring 85 clips away from the member 11 and inserting memorandum slips 32 between the spring clips and the member 11.

Connected with the front portion of the device, and adapted to coact with the front 90 wall 16, is a spring clip 33 for holding memorandum slips 34 adjacent to the front surface of the wall 16. The receptacle may be used for holding suitably indexed separator cards 35, and for holding memorandum slips of various kinds. 95

Arranged adjacent to the lower ends of the clips 30 are transverse strips 36, against which the lower edges of the memorandum slips supported on the member 11 may rest. 100

An office appliance of this kind may be put to a great variety of uses, and I will simply suggest possible uses for explaining the possible functions and utility of the device. 105

Assuming that the device is completed and assembled as shown, it then becomes a combined tickler and despatch board, suitable for the desk in any office. Memorandum or tickler slips 32, such for instance as 110 that shown in Fig. 5 are used for memoranda of any matter that needs to be given atten-

tion on any certain date. These memorandum slips 32, are inserted between the separator or guide cards 35, in the tickler box. These separator or guide cards 35, 5 are tabbed with month and dates of the month so that the tickler memoranda come up automatically on the desired date. When the date arrives the user of the device raises the cover and allows it to slide downwardly 10 behind the receptacle or tickler box. The slips for the date in question are removed from the receptacle or tickler box and sorted. The slips referring to matters demanding 15 immediate attention are sorted in the order of their importance, and are then mounted on the member 11, by slipping them under the upper spring clip 30, the most important and urgent being on top and plainly visible. Slips referring to matters not so pressing 20 are sorted in the order of their importance with the ones needing earliest attention on top and these are slipped under the lower clip 30, on the member 11. A slip referring to the appointments for the day may be 25 placed against the forward surface of the wall 16, and held in position by the clip 33.

It will be seen that the device is so arranged that the appointment slip and the top slips of those mounted on the member 11, are 30 plainly visible. When thus arranged on the despatch board, they constitute the schedule for the day's work. This facilitates the orderly planning of the day's work, and when once planned, the work can be despatched according to the schedule without 35 delay, uncertainty or confusion. The slips may be removed from the clips and re-arranged at any time, and a new schedule made to fit changing conditions, or new matters 40 that may come up. The current task in hand is always in plain sight before the eye, flagging the attention, and expediting the prompt despatch of the business as planned.

The device as a whole is designed in a 45 novel and convenient manner in order to give the maximum results in planning and scheduling the day's work with the minimum time and effort of a routine nature. The device is so arranged that an efficient schedule can 50 be quickly made up and quickly and conveniently adjusted ready for attacking the day's business.

The advantages of such an appliance may

be readily seen from the foregoing description, and it will be obvious that the advantages may be extended by using the appliance, for a great variety of purposes. 55

Some changes may be made in the construction and arrangement of the parts of the device without departing from the real 60 spirit and purpose of my invention, and it is my intention to cover by the claims hereinafter written, any such modifications as may be reasonably included within their 65 scope.

I claim as my invention:

1. In an office appliance, a base, an inclined member thereon near the rear part thereof, a holding device on said inclined member, a receptacle mounted on said base, forwardly 70 from said inclined member, and a cover hingedly and slidably mounted on said receptacle and adapted to be moved to position behind the receptacle.

2. In an office appliance, a base, an inclined 75 member thereon near the rear part thereof, a holding device on said inclined member, a receptacle mounted on said base, forwardly from said inclined member, and a cover hingedly and slidably mounted on said receptacle and adapted to be moved to position behind the receptacle, said receptacle having 80 inclined front and rear walls.

3. In an office appliance, a base, an inclined member thereon near the rear part thereof, a holding device on said inclined member, a receptacle mounted on said base, forwardly 85 from said inclined member, a cover hingedly and slidably mounted on said receptacle and adapted to be moved to position behind the 90 receptacle, said receptacle having inclined front and rear walls, and a device for holding memorandum slips on the front wall.

4. In an office appliance, a base, a member mounted thereon near the rear part thereof, 95 inclined upwardly and rearwardly, a holding device on said member, a receptacle on said base, spaced forwardly from said inclined member, a cover member for said receptacle, and means for mounting said cover member 100 pivotally and slidably on the receptacle, for permitting the cover to be raised and slid downwardly behind said receptacle.

Des Moines, Iowa, May 18, 1920.

DWIGHT G. McCARTY.
